X-RAY AND DIATHERMY CABLE

George S. Eager, Jr., Upper Montclair, N.J., assignor to General Cable Corporation, New York, N.Y., a corporation of New Jersey

Filed Aug. 31, 1964, Ser. No. 393,821

11 Claims. (Cl. 174—107)

This invention relates to electric cable and more especially to X-ray and diathermy cables and similar cables.

It is an object of the invention to provide novel high voltage flexible cable useful for X-ray and diathermy and similar equipment, and which is of simplified construction with resulting lower manufacturing cost.

It is a feature of the invention that neoprene insulation is used on the single conductors instead of the usual better grade insulation based on natural, SBR, or butyl rubber. By using the comparatively poor insulating neoprene compound, a semi-conducting shield becomes unnecessary.

Another object of the invention is to make the same compound useful for individually insulating two conductors and for covering over the two conductors.

Other advantages of the invention are that the cable is (1) smaller and lighter in weight, (2) more rugged and of better flexing life, and (3) a simplified design easier to manufacture.

Other objects, features and advantages of the invention will appear or be pointed out as the description proceeds.

In the drawing, forming a part hereof, in which like reference characters indicate corresponding parts in all the views;

FIGURE 1 is a fragmentary view showing one construction of a cable made in accordance with this invention;

FIGURES 2 and 3 are views similar to FIGURE 1 but showing modified forms of the invention;

FIGURE 4 is a sectional view taken on the line 4—4 of FIGURE 1; and

FIGURES 5 and 6 are sectional views, similar to FIGURE 4, but taken on the lines 5—5 and 6—6 of FIGURES 2 and 3, respectively.

FIGURE 1 shows an X-ray cable which includes two electrical conductors 11 and 12, preferably made of tinned copper. The conductors 11 and 12 are covered with tough neoprene rubber insulation 14 instead of the conventional insulation which is made of natural rubber or some other material which is superior to neoprene rubber as an electrical insulator. The valleys between the insulated conductors 11 and 12 are each filled with a group of small gauge copper wires 16.

A coating of the same neoprene rubber insulation 18 surrounds the group of conductors which consists of the individually insulated conductors 11 and 12 and the uninsulated groups of copper wires 16 which are located in the valleys on both sides of the individually insulated conductors 11 and 12, as clearly shown in FIGURE 4.

As an example, the conductors 11 and 12 may be No. 18 AWG copper wire covered with neoprene rubber insulation $\frac{1}{64}$ " in thickness, and each of the groups of wires 16 may include approximately 50 tinned copper wires which are No. 34 AWG. With this illustrative example, the neoprene insulation 18 around the group of conductors may be $\frac{1}{32}$ " in thickness.

Around the outside of the insulation 18, there is a layer of high grade electrical insulation such as butyl rubber insulation 20 and in the illustrated example this insulation 20 is approximately $\frac{1}{8}$ " thick; that is, it is approximately four times as thick as the insulation 18.

Around the outside of the insulation 20 which may

be made of natural, SBR or butyl rubber, or other flexible electrical insulating material of high grade insulating qualities, there is a semi-conducting layer 22. In the preferred construction of this semi-conducting layer is a tape helically wound around the insulation 20 and the tape may be a nylon rubber skim semi-conducting tape.

A wire braid 24 surrounds the semi-conducting layer 22. This wire braid 24 preferably made of tinned copper of approximately No. 34 AWG and has a minimum coverage of approximately 95 percent. In the preferred construction of the cable, an outer protecting braid 26 covers the wire braid 24. This outer braid 26 is preferably a woven fiber braid and can be made of nylon, preferably black nylon.

The insulated conductors 11 and 12 are twisted together and have their insulations 14 of different colors to provide color coding for the electrical system. These conductors 11 and 12 supply the filament current of the high voltage tube and the copper conductors 16 in the valleys supply the cathode or high voltage electrode. This invention embraces several basic changes in the conventional design and all of which are directed towards the elimination of the semi-conducting rubber; some of which result from the fact that the semi-conducting rubber has been eliminated.

The neoprene rubber insulation used for the insulating layers 14 and 18 must be chosen so as to have relatively poor electrical insulating properties. The insulation resistance must be less than 5 megohms per thousand feet of covered conductor when measured at room temperature. It must, however, have sufficient insulation resistance to maintain a low voltage for the filaments and this must be not less than about $\frac{1}{10}$ megohm per thousand feet at room temperature. Too low insulation resistance results in excessive leakage currents and too high insulation resistance results in excessive voltage drop across the insulation 18.

The dielectric strength must exceed 200 volts per mil of insulation; otherwise the insulation 14 will not support the filament voltage and the insulation 18 will not support the small but not zero voltage drop across it. An insulation with too good insulating properties as normally obtained with the insulation now used is not satisfactory for the construction shown in FIGURE 1. The semi-conducting rubber used for conventional X-ray cable is replaced with the neoprene.

Because of the fact that neoprene rubber has such a low insulation resistance compared to that of the insulating layer 20, the neoprene rubber will not permit a D.C. potential of any magnitude to develop across it and will function in a manner similar to the semi-conducting rubber conventionally used. The insulation layer 20 usually has an insulation resistance value of about 25,000 megohms per thousand feet based on a $\frac{1}{64}$ " wall, or about 5000 to 250,000 times higher than the neoprene rubber.

In the construction shown in FIGURE 1, it is not possible to replace the insulation 14 with semi-conducting rubber because the leakage currents would be excessive. The combination of the neoprene insulating layer 18 and the high grade insulating rubber layer 20 having approximately four times the radial thickness of the layer 18 does not function as a "graded" cable because with this invention the insulation 14 is of such poor insulation resistance so as not to support any significant portion of the voltage stress across this belt as would be the case in a graded cable.

The advantages of the changes in construction made by this invention are (1) a simplified construction because the use of semi-conducting rubber has been eliminated, and (2) easier manufacture of the cable because the fac-

tory does not have to be set up to extrude semi-conducting rubber in the same machine used for insulating.

FIGURE 2 shows another construction which is still further simplified as compared with that shown in FIGURE 1. Three conductors 31, 32 and 33, instead of being twisted together like the insulated conductors 11 and 12 of FIGURE 1, are maintained in spaced relation to one another while a neoprene secondary layer 35 is extruded around and between the conductors 31, 32 and 33 in the relation shown in FIGURE 5. The cross section of the layer 35 is circular and the outside diameter may be the same as the diameter of the outside of the insulation 18 of FIGURE 1.

In FIGURE 2, however, the neoprene rubber serves a dual purpose; it insulates the two filament conductors 31 and 33 and at the same time is sufficiently poor in insulating properties, as compared with the insulation 20 to function as a semi-conducting material does in that the radial D.C. voltage drop across it is negligible and the voltage stress is such that the stress is "smoothed" in a manner similar to that achieved by the semi-conducting rubber.

In order for the neoprene rubber of the layer 35 to serve this dual function, it must have low insulation resistance compared to the insulation 20 but still have high enough insulation resistance to support the filament voltage. This can be achieved if the insulation resistance of the material of the layer 35 is in the range of $\frac{1}{10}$ to 5.0 megohms per thousand feet and if the layer material at the same time has a high dielectric strength in excess of about 200 volts per mil. The parts of the construction shown in FIGURE 2, which are identical with that shown in FIGURE 1, are indicated by the same reference characters.

Another modification of the construction shown in FIGURE 1 is the elimination of the uninsulated wires 16 and the use of one or the other of the conductors 11 and 12 to serve as the inner high voltage lead which connects to the cathode.

Another modification is to replace the copper wires 16 of FIGURE 1 by a more flexible type of conductor; for example, a tinsel conductor. This provides increased flex life for the overall cable to compensate for some loss of the flex life which results from the fact that the copper wires 16 are not twisted together.

FIGURE 3 shows still another modification of the invention in which there is a central conductor 41 which is preferably made of tinned copper as in the case of the other conductors 11, 12 and 31, 32 and 33, and there is a coating of neoprene rubber insulation 44 around the center conductor 41. This neoprene rubber insulation 44 corresponds to the insulation 14 of FIGURE 1. Bare strands 45 of copper wire or other electrically conducting material are helically applied over the neoprene insulation 44 and the same kind of neoprene is applied as an outer insulation 46 which is similar to the insulation 18. The insulation 46 is covered with a layer of good quality insulation 20 and the other construction of the cable in FIGURE 3 is the same as in FIGURES 1 and 2 with identical and corresponding parts indicated by the same reference characters.

In all of the forms of the invention disclosed herein, a paper or plastic film separator can be used over the tinned copper conductors and under the neoprene. Such a separator serves to increase the flex life where the conductors are not twisted together and also serves as a means of polarity identification making it unnecessary to use colored insulation on the different wires.

The volume resistivity of the semi-conducting rubber used in X-ray cables is much lower than that of insulating rubber. The insulation resistance is in the range of 100 to 10,000 ohms per thousand feet of covered conductor when measured at room temperature. This compares to the range of $\frac{1}{10}$ to 5 megohms per thousand feet for the neoprene as previously mentioned. The low resistance of the semi-conducting rubber cannot support the filament

voltage without overheating as the result of excessive currents and therefore cannot be used in place of the neoprene on the conductors of this invention.

The preferred embodiments of the invention have been illustrated and described, but changes and modifications can be made, and some features can be used in different combinations without departing from the invention as defined in the claims.

What is claimed is:

10. A flexible cable for X-ray and diathermy and similar equipment including two or more flexible, metal, electrical conductors; neoprene rubber surrounding one or more of these conductors serving as an insulation, and a secondary neoprene layer serving the function of a semi-conducting covering; a layer of high-grade electrical insulation which is a rubber insulation based on material from the group consisting of natural, SBR and butyl rubber covering the circumferential extent of the neoprene rubber; a semi-conducting layer over said high-grade electrical insulation; and a protecting covering over the semi-conducting layer.
15. The flexible cable described in claim 1 characterized by there being two electrical conductors, each of which is individually insulated by a covering of neoprene rubber and both of which are enclosed in a common layer of neoprene rubber electrical insulation.
20. The flexible cable described in claim 2 characterized by at least one bare conductor in the valley between the individually insulated conductors, the bare conductor being enclosed with the individually insulated conductors in the same common layer of neoprene rubber electrical insulation.
25. The flexible cable described in claim 3 characterized by the conductors being twisted together and the outside of the neoprene rubber coating being substantially cylindrical.
30. The flexible cable described in claim 4 characterized by there being a plurality of electrical conductors spaced from one another and individually electrically insulated from one another by being embedded in a mass of neoprene rubber insulation that fills the space between the individual conductors and that extends radially beyond the individual conductors to form a core having a substantially cylindrical outside surface.
35. The flexible cable described in claim 1 characterized by the neoprene rubber that surrounds the conductor being itself surrounded by another conductor comprising a wire serve, and the wire serve being surrounded by neoprene rubber that serves the function of a semi-conducting covering.
40. The flexible cable described in claim 1 characterized by the protecting covering including a wire braid of tinned copper having a minimum coverage of 95 percent, and a full coverage woven cloth braid over the wire braid.
45. The flexible cable described in claim 1 characterized by the conductor being tinned copper wire.
50. The flexible cable described in claim 1 characterized by the semi-conducting layer being a nylon rubber skim semi-conducting tape applied in a helical wrap around the high grade insulation covering and with successive convolutions of the helix overlapping one another.
55. The flexible cable described in claim 1 characterized by the material of said layer of high grade insulation having an insulation resistance between 5,000 and 250,000 times higher than the resistance of the neoprene.
60. A flexible cable for X-ray and diathermy and similar equipment including a flexible, metal, electrical conductor, a flexible electrically insulating material of neoprene rubber surrounding the conductor and providing both insulation and a secondary common layer serving the function of a semi-conducting covering, a layer of high grade electrical insulation covering the circumferential extent of the neoprene rubber, and a protecting covering over the outside of the cable, the flexible electrically insulating material having insulation resistance less than 5

megohms per thousand feet of covered conductor at room temperature and greater than about $\frac{1}{10}$ megohm per thousand feet of covered conductor at room temperature.
